CLAIM

The design for goggles with full wrap unitary lens, as shown and described.

DESCRIPTION

FIG. 1 is a perspective view of goggles with a full wrap unitary lens showing a new design;

FIG. 2 is a top rear perspective view thereof;

FIG. 3 is a bottom rear perspective view thereof;

FIG. 4 is a top plan view thereof;

FIG. 5 is a front elevational view thereof;

FIG. 6 is a bottom plan view thereof;

FIG. 7 is a rear elevational view thereof;

FIG. 8 is a right side elevational view thereof; and,

FIG. 9 is a left side elevational view thereof.

The broken line showing of the goggle strap in FIGS. 1-3 is for illustrative purposes only and forms no part of the claimed design.
